UNITED STATES PATENT OFFICE.

VICTOR STROH, OF POPLAR BLUFF, MISSOURI.

ATTACHMENT FOR ADDING-MACHINES.

No. 829,387.

Specification of Letters Patent.

Patented Aug. 21, 1906.

Application filed November 3, 1905. Serial No. 285,800.

To all whom it may concern:

Be it known that I, VICTOR STROH, a citizen of the United States, residing at Poplar Bluff, Butler county, Missouri, have invented 5 a certain new and useful Improvement in Attachments for Adding-Machines, of which the following is a full, clear, and exact description, such as will enable others skilled in the art to which it appertains to make and use 10 the same, reference being had to the accompanying drawings, forming part of this specification, in which.

Figure 1 is a vertical sectional view 15 through my improved zero-printing attachment for adding-machines. Fig. 2 is a similar view showing the parts in a different position. Fig. 3 is a similar view showing the parts in still another position, and Fig. 4 is a plan view of the mechanism.

20 This invention relates to a new and useful improvement in adding-machines, and particularly to that class of adding-machines involving in their construction what is known as a "transversely-traveling stop-carriage," 25 whose stops are set in position by the operation of the various keys.

Heretofore in this class of machines there are usually ten digit-keys, numbered from 30 "1" to "9," inclusive, and also containing the zero character, which coöperate with one of a series of ten stops in a traveling carriage, there being as many series of stops (ten in each series) as required for the capacity of the machine. In certain types of this so-called "cross-carriage" machine there are 35 order-keys, which upon being operated predetermine the position of the carriage so that the first stop set up will be that of the highest order or denomination, the carriage 40 then traveling as each digit-key is struck in a step-by-step movement from left to right. In another type of cross-carriage machine there are no so-called "order-keys" present to predetermine the position of the carriage 45 but the successive operations of the digit-keys in addition to setting up the stops also effect the movement of the carriage from right to left—as, for instance, in setting up the item "\$1500.00" the "1" digit-key is 50 struck, then the "5" digit-key is struck, and then the "0" digit-key is depressed four times in succession, requiring six operations of keys and causing the carriage to move six steps from right to left, placing the stop set up by

the depression of the "1" key in the thousands-column, the "5" key in the hundreds-column, and the "0" in the tens, units, dimes, and cents columns. When the keys have been operated, as above described, to set up an example in the machine, a handle 55 usually located at the right-hand side of the machine is pulled forward to cause segmental racks to be moved until arrested by the stops in the path of projections on said racks, which position properly locates the 60 printing-type in printing line and also determines the extent of rotation of the totalizer-wheels in accumulating the item in the totalizer. My present invention does not comprehend in its scope any improvements in 65 the mechanisms of these existing machines, but relates to supplementary mechanism to be added to the type of cross-carriage machines referred to, whereby the operator is enabled to avoid the necessity of successively depressing the zero digit-key a number of times, as in the example of introducing the item "\$1500.00" above given.

In carrying out my present invention I add 70 to the keyboard of the adding-machine a series of keys containing zero characters preferably of large size and smaller numerals, as "1," "2," "3," &c., indicating the number of steps the carriage will be caused to move, and zero characters which will eventually be 75 printed upon the operation of the handle by the depression of any of the supplementary zero-keys. The number of zero characters to be added to any given machine depends 80 upon the capacity of the machine, there usually being one less than the actual capacity of the machine.

In the drawings I have shown a well-known 85 type of cross-carriage machine in which 1 is the base, and 2 the side frames extending up from the base, in which side frames are mounted the movable parts of the machine. 3 represents the so-called "numeral" digit-keys, (shown in dotted lines in Fig. 4,) which numeral digit-keys terminate at their 90 rear ends in longitudinally-aligned fingers arranged under the stops in the cross-carriage 4. For sake of convenience these cross-carriage stops are marked "0" "1" "2" "3" "4" "5" "6" "7" "8," indicating that 95 when one of said stops is elevated it will arrest the segmental rack in such position that the printing-type corresponding to the posi-

tion of the stop in the series will be arranged in printing line and also the totalizer-wheel of that order will be actuated a corresponding distance. There is no stop for the "9" key, 5 because when the "9" key is depressed the segmental rack moves forward the full limit. The stop-carriage is mounted on suitable rollers running on tracks 5 and is connected to the cable 6 of a spring-drum 7, which 10 tends to pull said carriage from right to left. The means for restoring the carriage to normal starting position forms no part of my present invention and is therefore not illustrated in the drawings. The escapement 15 mechanism for permitting the carriage to move one step toward the left at every depression of the numeral digit-keys up to the capacity of the machine is carried by a yoke-frame 8, swinging from a shaft 9 and carrying 20 a part of the escapement mechanism at its free end. By referring to Fig. 4 it will be observed that part of the mechanism for actuating the cross-carriage comprises a rack 10, mounted on the carriage, and a segmental gear 11 in mesh with said rack.

So far as the above construction is concerned it forms no part of my present invention, and I have referred to it herein only for the purpose of showing the relation of my 30 improvement to the type of adding-machine embodying the above-described features.

12 indicates a series of keys which may be designated as "zero-keys" to distinguish them from the ordinary digit-keys of the machine, and, as shown in Fig. 4, these keys 35 bear the characters "0¹," "0²," "0³," "0⁴," "0⁵," "0⁶," "0⁷," and "0⁸." The shanks of these keys respectively are connected to the ends of levers 13, pivotally mounted in a 40 suitable frame extending up from the base, the rear ends of each of said levers terminating in a stop 14. 15 is a sliding member provided with a stop projection 16 at its rear end in longitudinal alinement with the stops 14.

45 The sliding member and its projection 16 are normally held in forward position by a spring 17. On the under side of the sliding member are ratchet-teeth for cooperating with a pivoted pawl 18, carried by a sliding bar 19, 50 mounted in suitable posts on the base. A spring 20 exerts pressure upon the bar 19, tending to move the same rearwardly at all times. The forward edge of the bar 19 is provided with a series of ratchet-teeth which 55 operate with a pawl 21, pivoted in a post 22, extending up from the base and having a spring 23 connected to its forward end, tending to hold the rear end of the pawl in engagement with the teeth of the bar 19. The 60 forward end of pawl 21 carries a cross-bar 24, which is arranged across the stop-carrying levers 13, and also a lateral projection 24^a, which extends under the pawl 18.

The operation of the above-described parts 65 is as follows: When the zero-key is depressed,

as shown in Fig. 2, one of the stops 14, in this instance the stop controlled by the zero-key "0⁸," will be elevated and in so doing, by means of the lateral projection 24^a, raise the pawl 18 into engagement with the forward 70 tooth on the sliding member 15 and by means of the bar 24 depress the rear end of pawl 21 out of engagement with the rear tooth of the bar 19, permitting said bar to move rearwardly under the impelling action 75 of its spring and carry with it the sliding member 15 until the projection 16 is arrested by the elevated stop 14. The depression of any of the key-shanks 12 operates a bar arranged under the lower ends thereof carried 80 by a bell-crank lever 25. This bell-crank lever is connected by a rod 26 to a lever 27, attached to a part of the escapement mechanism, so that whenever one of the zero-keys is depressed and previous to the commencement 85 of the movement of bar 19 rearwardly to a position determined by one of the stops 14 the escapement mechanism is disengaged, so as to permit travel of the cross-carriage 90 independently of the control of said escapement mechanism. This is accomplished by making the side members of the yoke 8 in sections, one of which, 8^a, upon which the escapement mechanism is mounted, is capable of sliding movement with respect to the 95 hinged portion of the yoke-frame by means of a slot-and-pin connection, as shown in the drawings. The light spring tends to assist the return of the movable section of the yoke member carrying the escapement mechanism to normal position when the zero-key is 100 released.

A continuation 26^a of the rod 26 is connected to a bell-crank lever 28, whose other member is connected by a link 29 to the hub 105 of a pinion 30, slidable in a vertical direction on the shaft 31. Meshing with this pinion and fixed on the shaft 11^a, on which the segmental gear 11 is mounted, is a segmental gear 32.

In the ordinary operation of the machine, whenever one of the numeral digit-keys is depressed, the segmental gears 11 and 32 are actuated, but the pinion 30, in its lowermost position, is rotated idly. When, however, the pinion 30 is raised by the depression of one of the zero-keys, it is thrown into mesh with rack-teeth 33 on the rear end of bar 19, so that the rearward movement of the bar will rotate the pinion 30, which is 115 constantly in mesh with the segmental rack 32 irrespective of the position of the cross-carriage, and through the segmental rack 11 move the cross-carriage along its track until the bar 19 is arrested. This movement of the 120 cross-carriage causes a projection 34, carried by one of the movable arms of the yoke, to be placed under the zero-stop bars in the cross-carriage, and consequently when said cross-carriage moves such zero-stop bars as ride 125 130

over the projection 34 will be elevated into the path of the projection 35 on the segmental gear 36 of the machine.

When the zero-key is released, as shown in Fig. 3, the escapement mechanism is restored to normal position, and with such restoration the zero-stop-elevating projection 34 is restored to its normal inoperative position. Pinion 30 is also moved out of mesh with the rack-bars 33. As the "0" zero-key has been depressed, it will be seen by reference to Fig. 2 that the bar 19 has been moved to the full limit of its travel. We will assume, however, for purposes of illustration that it is desired to set up the item "1500.00" on the keyboard, in which event the "1" and "5" digit-keys are struck and then the zero-key "0" is operated. Under the old system it would be necessary in setting up the same example after depressing the order-key and the numeral digit-keys "1" and "5" to depress the "0" key four times. It will thus be seen that by the use of my improvement in the particular instance given the one zero-key "0" accomplishes the same result as four depressions of the zero-key under the old arrangement.

Where no order-keys are employed on the machine, it will be obvious that in setting up the aforesaid example it is only necessary to depress the "1" and "5" digit-keys and the "0" key. In the event that it was desired to set up an example of, say, "\$1,050,005.00" the "1" digit-key would be struck, then the "0" zero-key. This zero-key would permit the bar 19 to move rearwardly until arrested by the appropriate stop. Then when the zero-key was released the pawl 21 would move up into engagement with the second tooth from the rear of bar 19 and the sliding member 15 would be released by the pawl 18, said sliding member returning to normal position. The release of the zero-key also restores the pinion 30 and the escapement mechanism to normal position, so that the "5" digit-key could be depressed. The next operation would be the depression of the "0" zero-key, and when said key was depressed the pawl 18 would be forced up into engagement with the second tooth from the front of the member 15 and the pawl 21 moved out of engagement with the bar 19, permitting said bar to move rearwardly a distance equal to three of the ratchet-teeth and until arrested by the stop controlled by the "0" zero-key. When the "0" zero-key was released, the sliding member 15 would be restored to normal position and the bar 19 held in its new position by the reengagement of the pawl 21 therewith. The next operation would be the depression of the "5" digit-key and finally depressing the "0" zero-key, which will cause the reengagement of pawl 18 with the sliding member 15 and the disengagement of the pawl 21 from the bar 19, permitting the

bar 19 to move rearwardly an additional distance equal to two of its ratchet-teeth. Of course it will be understood that the operation of several multiple zero-keys effects the inoperativeness of the escapement mechanism and the elevation of pinion 30, the release of said keys restoring the escapement mechanism and lowering said pinion 30. I prefer to leave in the bank of numeral-keys the usual tenth or digit key to operate the spacing mechanism, as is now commonly practiced in order to throw up the proper stop to print the zero character in the printing line. By so leaving this old zero-key in the numeral digit-bank the same may be operated, if desired, in the old manner by an operator accustomed thereto. The movement of the handle in placing an item in the machine also restores the bar 19 and the parts of the multiple-key mechanism to normal position. On the power-shaft of the machine, upon which the handle is usually mounted, is arranged a rock-arm 37, carrying a roller at its end which engages a shoulder 88 on the bar 19, and thus the forward movement of the handle restores the bar to its normal position.

I am aware that minor changes in the construction, arrangement, and combination of the several parts of my device can be made and substituted for those herein shown and described without departing from the nature and principle of my invention.

Having thus described the invention, what is claimed as new, and desired to be secured by Letters Patent, is—

1. In a machine of the character described, the combination with digit-keys and multiple zero-keys, stops under control of said keys, and means for setting up a selected number of stops by the operation of a single multiple zero-key; substantially as described.

2. The combination with a traveling carriage and its stops, a key, and means for setting up a plurality of stops in the carriage and advancing said carriage a distance greater than one space by the single operation of said key; substantially as described.

3. The combination with a traveling carriage and its stops, means for advancing the carriage a distance greater than one denomination, and means capable of being positioned by the operator, whereby, the advancing movement of the carriage sets up a number of stops corresponding to the denominations advanced by the carriage; substantially as described.

4. In a machine of the character described, the combination with keys and selectable stops, of means under the control of a single key for successively cooperating with a plurality of said stops; substantially as described.

5. In a machine of the character described, the combination with selectable stops, of a

- plurality of multiple zero-keys, and means under the control of a single key for successively coöperating with said stops upon a single depression thereof; substantially as described.
5. In a machine of the character described, the combination with a traveling carriage containing stops, and means capable of being placed in the path of a transverse series of stops for moving said stops into an operative position; substantially as described.
6. In a machine of the character described, the combination with a group of key-operated stops arranged in longitudinal and transverse series, and key-controlled means for moving a selected number of said stops into operative position by a single depression of a key; substantially as described.
15. In a machine of the character described, the combination with means for determining the printing position of the printing-type including the printing of zero characters, and mechanism controlled by the single operation of a key for controlling a selected number of said positioning means; substantially as described.
20. In a machine of the character described, the combination with a keyboard composed of numeral digit-keys and multiple zero-keys and stops identified with different denominations, two or more of which are positioned by the operation of any one of said multiple zero-keys; substantially as described.
25. A machine of the character described having a keyboard composed of numeral digit-keys and multiple zero-keys and stops identified with different denominations, two or more of which are positioned by the operation of any one of said multiple zero-keys; substantially as described.
30. A machine of the character described having a keyboard composed of numbered digit-keys and multiple zero-keys, the latter bearing zero characters indicating the number of zeros to be introduced into the machine and stops identified with different denominations, two or more of which are positioned by the operation of any one of said multiple zero-keys; substantially as described.
35. A machine of the character described having a bank of numeral digit-keys including a key having a zero character, and also a bank of multiple zero-keys; substantially as described.
40. A machine of the character described having a bank of numbered digit-keys and multiple zero-keys, the latter bearing zero characters indicating the number of zeros to be introduced into the machine and stops identified with different denominations, two or more of which are positioned by the operation of any one of said multiple zero-keys; substantially as described.
45. A machine of the character described having a bank of numeral digit-keys including a key having a zero character, and also a bank of multiple zero-keys; substantially as described.
50. A machine of the character described, the combination with a series of zero-stops identified with the different denominations, a bank of multiple zero-keys, and mechanism controlled by each multiple zero-key for moving two or more zero-stops into operative position; substantially as described.
55. A machine of the character described, the combination with a series of zero-stops identified with the different columns or denominations, a bank of multiple zero-keys, stops controlled by said bank of keys, and mechanism for moving a selected number of zero-stops into operative position as determined by the extent of movement permitted by the key-stops; substantially as described.
14. In a machine of the character described, the combination of a series of digit-key-operated stops, and mechanism for moving said stops into operative position independently of the operation of said digit-keys; substantially as described.
15. In a machine of the character described, the combination with digit-keys, stops operated by said digit-keys, multiple zero-keys, and means operated by each multiple zero-key for positioning two or more of said stops; substantially as described.
16. In a machine of the character described, the combination with digit-key-operated stops, and means connected with multiple zero-keys for operating a selected number of said stops by a single operation of one of said multiple zero-keys; substantially as described.
17. In a machine of the cross-carriage type, the combination with a transversely-movable stop-carriage and its escapement mechanism, of a multiple zero-key, and means connected to said key for moving said escapement mechanism to an inoperative position and advancing the traveling carriage a predetermined distance; substantially as described.
18. In a machine of the cross-carriage type, the combination with a transversely-movable carriage and its stops, of means for moving said carriage, an escapement mechanism, a multiple zero-key, connection between said key and said escapement mechanism for rendering the latter inoperative when said key is depressed, and means also connected to said multiple zero-key for moving a selected number of zero-stops in said carriage into an operative position when said key is depressed; substantially as described.
19. In a machine of the character described, the combination with a transversely-movable carriage and its stops, means for moving said carriage, escapement mechanism which is operated by the number-bearing keys to advance the carriage step by step, a plurality of multiple zero-keys, mechanism common to all of said keys for rendering the escapement mechanism inoperative when any one of said multiple zero-keys is depressed, a stop controlled by each of said multiple zero-keys, a bar whose movement is determined by said stops, means operated by any one of said keys for releasing said bar, and mechanism operated by said bar for causing the carriage to be advanced, and a selected number of zero-stops to be thrown into operative position; substantially as described.
20. A machine of the character described provided with means for setting up a plurality of stops by the operation of a single key, and mechanism operated by the power-shaft of the machine for restoring said means; substantially as described.
21. In a machine of the character described, the combination with stops, multiple zero-

keys, any one of which is capable of positioning two or more of said stops, and a power-shaft for restoring the operated parts to normal position; substantially as described.

22. In a machine of the character described, the combination of mechanism for setting up a selected number of stops by the single operation of a key, and means connected to the power-shaft of the machine for restoring said

mechanism to normal position; substantially as described.

In testimony whereof I hereunto affix my signature, in the presence of two witnesses, this 30th day of October, 1905.

VICTOR STROH.
